UNITED STATES PATENT OFFICE.

HOWARD S. ROBERTS, OF WASHINGTON, DISTRICT OF COLUMBIA, ASSIGNOR TO
CARNEGIE INSTITUTION OF WASHINGTON, OF WASHINGTON, DISTRICT OF COLUMBIA.

MICROFURNACE.

Application filed May 15, 1925. Serial No. 30,633.

By the microscopic study of coals and carbonaceous shales a large amount of information has been obtained as to the botany of the plants which contributed to their formation. In the continuance of these investigations it was found desirable to heat thin sections of the coal or shale in an inert atmosphere and to observe the phenomena which take place such as the melting and 10 volatilization thereof and the temperatures at which the phenomena occur. This was first done by a small resistance furnace of the cylindrical type, but this was inadequate for the examination of much of the material since the minute detail of the specimens in many cases necessitated the high magnification thereof for proper study.

In the case of the cylindrical furnace referred to, as is the case with all furnaces 20 hitherto used in high temperature microscopy, the specimen to be examined is placed within a heated chamber; it is supplied with heat, chiefly by radiation and convection, from the walls of the chamber, and loses 25 heat by radiation outward thru the openings which must be provided for observing the specimen. In order to increase the useful magnification of the specimen the solid angle subtended at the specimen by these openings must be increased. Thus it is 30 found that to attain a useful magnification of 300 diameters most of the heating must be from the sides of the specimen and as a consequence it is impossible to obtain a sufficiently uniform temperature across the 35 extent of the specimen or to measure its temperature with sufficient accuracy.

In the furnace which forms the subject matter of the present invention heat is supplied 40 to the specimen chiefly by conduction thru two strips of silica glass or other transparent material, being placed between them and in contact with both. The strips in turn are placed between and in good thermal 45 contact with two flat heating elements. Since the heating elements are close to the specimen the openings for observing the specimen may be kept small without constricting the large angle of view necessitated 50 by the high magnification desired. As a consequence the temperature across the specimen is sufficiently uniform. The temperature of the specimen is measured in the usual

way by means of a thermocouple whose junction is welded to one heating element or 55 located at definite point between the two heating elements, an experimentally determined correction being applied to allow for whatever difference there may be between the temperature of the thermocouple junction and that of the specimen.

This furnace permits the heating to high temperatures under such conditions as permit the employment of a microscope objective of large aperture having a working distance as small as 5 millimeters while keeping the objective reasonably cool. It is possible to measure the temperature readily and with sufficient accuracy. Oxidation of the specimen is prevented by keeping the furnace closed and passing a current of helium or other inert gas through it to exclude the air.

Other objects of the invention will be apparent from the following detailed description and the appended claims.

In the drawings:

Figure 1 is a side elevation of a microscope with the furnace in place on the supporting table or stage thereof.

Figure 2 is a perspective view of the furnace.

Figure 3 is a top plan view of the furnace with parts broken away.

Figure 4 is a longitudinal section on the line 4—4 of Figure 3.

Figure 5 is a transverse section on the line 5—5 of Figure 3.

Figure 6 is a transverse section on the line 6—6 of Figure 3.

Figures 7 to 13 inclusive disclose a modified form of furnace.

Figure 7 is a top plan view thereof.

Figure 8 is a section on the line 8—8 of Figure 7.

Figure 9 is a section on the line 9—9 of Figure 7.

Figure 10 is a similar section with the top removed.

Figure 11 shows two forms of one element 100 of the heater.

Figure 12 is a cross section of the heater.

Figure 13 is a perspective view of the heater, its support, and the thermocouple.

In the form of the invention disclosed in Figures 1 to 6, inclusive, the furnace is sub-

stantially rectangular and adapted to be placed upon the table A of a microscope B of any usual or desired type. The furnace casing is composed of an upper brass plate 1 and a lower brass plate 2 which form a relatively massive brass housing adapted to contain the elements to be described. The upper plate 1 has an internal conduit 3 to which water may be admitted by pipe 4 and from which it is discharged by pipe 5 or vice versa. Similarly the lower plate 2 has an internal conduit 6 to which water may be admitted by pipe 7 and may be discharged by pipe 8 or vice versa. The pipes 5 and 7 may be connected by a short tube 9 if desired and a continuous circulation of water is thus provided for. The two portions of the casing may be connected by screws 2'.

20 The heating element is a thin ribbon of nichrome bent double so as to form, in effect, two substantially plane and parallel heaters, 11 and 12. The upper end 10 of the ribbon is turned up adjacent the outside of the casing, and the lower end 13 turned down outside the casing. The end 10 is fastened by screws 14 to a terminal block 15 which is insulated from the casing as indicated at 16 and 17, and this terminal block is fastened 25 to the casing by screws 18 which are also provided with insulation 19 as shown in Figure 6. The screws hold in position the lead-in member 20 to which one of the circuit wires 21 may be attached. The circuit 30 is completed through the heating element, the end 13 of which is attached to the lower member 2 of the casing by screws 22 and through the casing member 2 to the lead-out member 23 attached by screws 24 to said lower member 2 and to which the other circuit 35 wire 25 may be attached.

Aligned openings 26 and 27 are provided in the heating element in order to see through it. The spaces above and below 40 the heater are filled with strips of mica 28 and 29 which have been previously heated for some hours at a temperature of about 950° C. which drives off the water and causes the mica to swell to several times its original 45 thickness. It thus forms a fairly good thermal insulator and at the same time has sufficient mechanical strength to keep the heater centered. Openings 30 and 31 are provided in the strips of mica in register with the 50 openings 26 and 27. Similar openings 32 and 33 are formed in the brass sections or plates 1 and 2, and in these are placed windows 34 and 35 of thin silica glass.

60 The temperature of the furnace is measured by a thermocouple 36 having its junction 37 located in a notch 38 in the porcelain block 39 which is placed between the layers 11 and 12 of the heating element. The wires of the thermocouple may pass out through 65 glass tubes 40 and 41, and the thermocouple

will be calibrated by noting its readings when a standard substance in the furnace is held at its melting point.

In order to prevent oxidation of the material being investigated it is in many cases 70 found desirable to fill the furnace with an atmosphere of helium or some similar inert gas. This is admitted to the body of the furnace through the pipe 42 and will escape through the opening 43 through which the 75 slides are introduced.

The specimen to be investigated is placed 80 between two silica glass strips 44 and 45 and may be introduced through the opening 43 and moved about considerably without 85 moving the furnace. If the furnace is filled with an atmosphere of helium, the heater requires a current of about 40 amperes to reach 900° C. and this may be supplied in any desired manner, as by an 11 volt sign-lighting 95 transformer controlled by a rheostat and ammeter in series with the primary winding of the transformer.

The modification illustrated in Figures 7 100 to 13 inclusive involves the same fundamental principles but differs considerably in detail. In this form the casing consists of a base member 46 substantially circular and adapted to fit in a similarly shaped opening 105 in the table A of the microscope and be supported thereon by a flange, and a top member 47, the two members being screw threaded 110 to engage as at 48. The opposing central portions of the two parts are hollowed 115 to form a chamber 49. A pipe 50 admits 120 water into a conduit 51 in the upper member 47 and the water passes off through a pipe 52. A similar conduit 53 in the lower member has an inlet connected to a pipe 54 and an outlet 55. An observation opening 125 56 in the upper casing member 47 is provided with a glass window 57 and a similar opening 58 in the lower member is provided with a glass window 59. Helium or other 130 inert gas is supplied to the chamber 49 through a pipe 60.

The heating element comprises an open ended silver box 61 shown in perspective in Figure 13, in longitudinal section in Figures 9 and 10, in cross section in Figure 12, and also diagrammatically in longitudinal section in Figure 11. This box has thin 135 layers of mica 62 on its sides and is wound with a fine resistance wire 63, (e. g. nichrome chromel, etc.), one terminal 64 of which passes out through a glass tube 65 and the other terminal 66 through a similar tube 67, the wires and tubes being preferably sealed with cement or otherwise to prevent diffusion of air into the chamber 49. The upper 140 and lower sides of the box will be formed with openings 68 and 69 respectively if the specimen is to be examined by transmitted light, or may be formed with an opening 70 in the upper side alone if the specimen 145

is to be examined by reflected light, the two forms being shown in Figure 11. It is obvious that the upper and lower sides of the box correspond to the upper and lower portions 11 and 12 of the ribbon in the form of furnace shown in Figures 1 to 6.

This heating element is supported in the chamber 49 by two identical supporting elements 71, each comprising a unitary member having feet 72 through which pass screws 73 which secure the member to the lower or base member 46 of the casing, and each having at its top two inturned ears 74 which fit into the open ends of the box 61 as clearly shown in Figure 13. These supports are very light and may each be stamped out of a piece of sheet metal of some alloy of low thermal conductivity.

The two wires, 76 and 77, which form the thermocouple are here welded to the silver box 61, one on either side of and close to the upper opening 68 with the two wires 76 and 77 leading off as shown in Figure 7 and Figure 13.

To position the specimen it is necessary to unscrew the top member 47 of the casing, after which the specimen, enclosed between two transparent plates as usual, can be introduced into the interior of the heating element through an open end as indicated at C in Figure 10.

Either form of the invention permits the specimen to be heated to a high temperature which may be measured and varied at will, and maintained at a remarkably uniform temperature during its examination through a high power microscope. It is obvious that various details may be changed and that portions of the invention may be used alone or in other combinations without in any way departing from the spirit of the invention which is to be regarded as limited only by the scope of the appended claims.

I claim as my invention:

1. A micro-furnace comprising a casing having a central chamber and a heating element within said chamber and having upper and lower portions spaced apart sufficiently so as substantially to contact with and surround a specimen carrying slide inserted therebetween.

2. A micro-furnace comprising a casing having a central chamber, a heating element within said chamber and having upper and lower portions spaced apart sufficiently so as substantially to contact with and surround a specimen carrying slide inserted therebetween, and means for cooling the casing.

3. A micro-furnace comprising a casing having a central chamber, a heating element within said chamber and having upper and lower portions spaced apart sufficiently so as substantially to contact with and surround a specimen carrying slide inserted therebetween, and conduits in said casing

through which water is circulated for cooling the casing.

4. A micro-furnace comprising a casing having a central chamber, a heating element within said chamber and having upper and lower portions spaced apart sufficiently so as substantially to contact with and surround a specimen carrying slide inserted therebetween, and means for introducing inert gas into said chamber.

5. A micro-furnace comprising a casing having a central chamber, a heating element within said chamber and having upper and lower portions spaced apart sufficiently so as substantially to contact with and surround a specimen carrying slide inserted therebetween, means for cooling said casing, and means for introducing inert gas into said chamber.

6. A micro-furnace comprising a casing having a central chamber, a heating element within said chamber and having upper and lower portions spaced apart sufficiently so as substantially to contact with a specimen carrying slide inserted therebetween, a block between and contacting with said portions, and a thermocouple carried by said block.

7. A micro-furnace comprising a casing having a central chamber, a heating element within said chamber and having upper and lower portions spaced apart sufficiently so as substantially to contact with a specimen carrying slide inserted therebetween, a block between and contacting with said portions, a thermocouple carried by said block, and means for introducing inert gas into said chamber.

8. A micro-furnace comprising a casing having a central chamber, and a heating element in the form of a nichrome ribbon supported in said chamber with its sides spaced apart sufficiently so as substantially to contact with and surround a specimen carrying slide inserted therebetween.

9. A micro-furnace comprising a casing having a central chamber, a heating element in the form of a nichrome ribbon supported in said chamber with its sides spaced apart sufficiently so as substantially to contact with a specimen carrying slide inserted therebetween, and layers of mica between the sides of said ribbon and the casing.

10. A micro-furnace comprising a casing having a central chamber, a heating element in the form of a nicrome ribbon supported in said chamber with its sides spaced apart sufficiently so as substantially to contact with a specimen carrying slide inserted therebetween, and layers of mica between the sides of said ribbon and the casing, said casing, heating element, and mica being provided with aligned observation openings.

11. A micro-furnace comprising a casing having a central chamber, a heating element in the form of a nichrome ribbon supported

in said chamber with its sides spaced apart sufficiently so as substantially to contact with a specimen carrying slide inserted therebetween, and layers of mica between the sides 5 of the ribbon and the casing, the ends of the ribbon being extended to the outside of the casing for connection to the terminals of a circuit.

12. A micro-furnace comprising a casing 10 having a central chamber, a heating element in the form of a nichrome ribbon supported in said chamber with its sides spaced apart sufficiently so as substantially to contact with a specimen carrying slide inserted there- 15 between, and a thermocouple lying between the sides of the ribbon and substantially sur- rounded thereby.

13. A micro-furnace comprising a casing 20 having a central chamber, a heating element in the form of a nichrome ribbon supported in said chamber with its sides spaced apart sufficiently so as substantially to contact with a specimen carrying slide inserted there- 25 between, layers of mica between the sides of the ribbon and the casing, and means for cooling the casing.

14. A micro-furnace comprising a casing 30 having a central chamber and a heating element therein in the form of a ribbon of metal folded to form spaced upper and lower por- 35 tions having their ends extended to the outside of the casing for connection to the terminals of a circuit, said upper and lower portions adapted to receive between them a specimen carrying slide.

15. A micro-furnace comprising a casing

having a central chamber, a heating element therein in the form of a ribbon of metal 40 folded to form spaced upper and lower por- tions having their ends extended to the outside of the casing for connection to the terminals of a circuit, said upper and lower por- tions adapted to receive between them a specimen carrying slide, and a thermocouple 45 located between the sides of the ribbon and adjacent said slide.

16. A micro-furnace comprising two heat- 50 ing elements having substantially plane par- allel surfaces separated by a short distance, aligned openings through each heating ele- 55 ment for observation, in combination with a slide comprising strips of transparent mate- rial carrying between them the specimen, said slide being in good thermal contact with the heating elements when placed there- between.

17. A micro-furnace comprising two heat- 60 ing elements having substantially plane par- allel surfaces separated by a short distance, aligned openings through each heating ele- 65 ment for observation, in combination with a slide comprising strips of transparent mate- rial carrying between them the specimen, said slide being in good thermal contact with the heating elements when placed there- between, and a thermocouple between said heating elements and adjacent the specimen to indicate the temperature of the latter.

In testimony whereof, I have hereunto sub- scribed my name.

HOWARD S. ROBERTS.
